UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed June 11, 1921. Serial No. 476,765.

To all whom it may concern:

Be it known that I, JOHN WALDHEIM, a citizen of the United States, residing in Elizabeth, in the county of Union and State of New Jersey, have invented certain new and useful Improvements in Typewriting Machines, of which the following is a specification.

This invention relates to sound-deadening cases or hoods for typewriting machines, and is of the same general type as that disclosed in the application of B. C. Stickney, Serial No. 429,617, filed December 10, 1920.

It has been proposed to make the hoods of various sections so that they may be disassembled and packed for shipment, the sections being secured to one another by screws.

An object of the present invention is to so construct the hood that it may be set up by any layman without difficulty. To this end the hood is composed of several sections which swing about one another so that the hood may be collapsed or folded; or set up; the various parts when swung assuming their proper positions. For this purpose, the casing comprises two main parts, viz., a body part, and a cover part hinged to said body part, said body part having a removable front wall to permit insertion of the machine, and comprising a rear member and side members hinged to said rear member. Thus, when the front plate is removed, the casing may be folded to occupy a small space without disassembling the body part from the cover part. For this purpose the side members may be folded against the rear member and the latter swung upwardly about the hinge which connects the cover part to the body part. The rear member, together with the side members which are attached thereto, may be swung into the cover part. The entire hood, therefore, for purposes of shipping, occupies substantially the same space as the cover part alone. Locking means may be provided to lock the side members against movement when the casing is set up, and, for this purpose, spring catches may be mounted on the side members to engage the rear member when the side members are swung outwardly to effective positions. The spring catches may be released when it is desired to swing the side members inwardly against the rear member.

The casing thus comprises a minimum number of parts and may be rapidly set up by merely swinging the rear member and the side members which it carries downwardly out of the cover part and swinging the side members outwardly from the rear member, said side members being fixed in outward or effective positions by the spring catches heretofore mentioned, and by attaching the front plate to the front of the side members.

Other features and advantages will hereinafter appear.

In the accompanying drawings,

Figure 1 is a vertical section of the casing or hood applied to an Underwood standard typewriting machine.

Figure 2 is a plan view of the hood, the cover part having been removed.

Figure 3 is an end view of the casing in its folded position.

Figure 4 is a fragmentary front view, in section, showing the relation of the side walls of the body part and the cover part.

The Underwood standard typewriting machine comprises a main frame 10 resting upon a base 11 by means of feet 12 attached to said frame, said main frame having a forward extension 13, in which are positioned banks of keys 14 for operating type-bars, not shown, to cause types carried by said type-bars to print against a platen 17. Said platen is journaled in end walls 18 of a platen-frame 19, forming part of a carriage 20 mounted for letter-feeding movement on a front rail, not shown, and a rear rail 21 on the main frame. The carriage is provided with forwardly and downwardly-extending operating levers, such as the line-space lever 22, carriage-return lever 23, and carriage-release lever 24.

For deadening the sounds arising in the typing operation, there is provided a sound-deadening casing or hood comprising a body part 30 and a cover part 31 connected to the body part at the rear by a hinge 32 formed by co-operating knuckles 27 and 28 on the body part and cover part, respectively, and a pivot-rod or bolt 29 passing through said knuckles. The body part comprises a rear member 33, having side extensions or pockets 34 for accommodating the work-sheets which hang from the rear of the carriage, side members 35 provided with extensions 36 over which the carriage operates to the

right and left, said side members having short front walls 37 between which is a large opening permitting the insertion of the machine from the front, and a front 5 plate 38 for closing the front opening after the machine has been inserted, said front plate being attached to said front walls 37 in any convenient manner, as by means of bolts 40 passing through co-operating lugs 41 and 42 on the front plate and the front walls, respectively. The front plate 38 is provided with an opening large enough to permit the forward extension 13 of the main frame to project therethrough. The machine is thus enclosed at the rear, front and sides, and, to enclose the machine at the top, there is provided the cover part 31 having a rear wall 31^a, a ceiling 43 extending forwardly and downwardly and terminating in 20 a front wall 44 above the front plate 38, said ceiling 43 being provided with a transparent plate 45 to permit typewriting at the interior of the casing to be viewed when the cover is in lowered position. A longitudinal 25 slot is formed at the front between the front wall 44 and front plate 38, through which project the operating levers 22, 23 and 24, so that the ordinary typing operations may be carried on without removing the cover. 30 For closing all of the slot not actually occupied by these levers, there are provided co-operating cushions 50 and 51 in the form of loops of sound-deadening material, such as plush, felt, or soft leather, the two-ply 35 margins of said loops being clamped between bars 52 to form units, which are mounted on the front wall 44 and the front plate 38, so that the folds contact. The passage or operation of the levers distorts 40 the cushions, which, however, are sufficiently resilient to return to their initial positions as soon as the distorting force is removed.

When the casing is to be packed for shipping, it is first removed from the machine 45 by withdrawing bolts 40 from lugs 41 and 42 to permit the front plate 38 to be detached, so that the typewriting machine may be removed from the casing. The side members of the body part may then be 50 folded inwardly to ineffective positions against the rear member by swinging each side member upon a hinge 53 formed by a bolt 54 passing through co-operating lugs or knuckles 56 and 57 on the side members 55 and rear member, respectively. The side members will then assume the position shown by the dot-and-dash line in Figure 2. The rear member may then be swung upwardly about hinge 32 to the interior of the 60 cover part, as shown in Figure 3. The extreme side walls of the rear member of the body part, which are the side pieces or walls 70 at the outer ends of pockets 34 are positioned to telescope within the side walls 65 71 of the cover part, so that said body part

may swing within the cover part (see Figure 4). To support the side walls 71 of the cover part, there are provided ledges 72 on the extensions 36 which extend outwardly beyond the side pieces 70. The ledges 72 do not interfere with the upward movement of the body part into the cover part, since the side members are first swung inwardly against the rear member, the extensions 36 and ledges 72 being thus moved out of the way of side walls 71. Strips of felt 73 may be applied to the ledges 72 as is usual in this type of hood to prevent noise being made when closing the hood by the cover.

To set up the casing, it is only necessary 80 to swing the body part downwardly about hinge 32, and swing side members 35 outwardly about hinges 53 until the rear edges 55 of the side members strike against the rear member. The side members are then 85 in their outward or effective positions, and are each held in such position by a catch 60 mounted on the side member and having a cam-surface 61 which rides upon a ledge or projection 62 on the rear member, during 90 the outward movement of the side pieces, until the nose 63 of the catch has passed the projection 62, and is snapped into engagement therewith by a spring 64 fixed to the side member and pressing against the catch. 95 When the nose of catch 60 has engaged the projection 62, inward movement of the side member is impossible. The catch may be released by moving it against the action of spring 64 until the nose 63 disengages projection 62, the catch being moved by means of a finger-piece 65. The casing is positioned on the base 11, said body part having inwardly-turned flanges 76 to aid in supporting the casing, and the typewriting machine is then inserted from the front and positioned within the body part by abutments 77 fixed to the rear member. The front plate 38, which is shorter than the distance between the side walls 71 of the cover 100 (Figure 2), is then applied and bolts 40 inserted in co-operating lugs 41 and 42 to hold the front plate in position, abutments 78 carried by the front plate co-operating with abutments 77 to hold the machine against movement within the casing. A work-sheet may then be inserted in the machine, the cover of the casing lowered, and the typing operation carried on in the usual manner.

Thus it will be understood that the various sections composing the hood are displaceable by swinging them so that the hood may be collapsed or folded for shipment and also readily set up for use. The collapsible hood may be lined with any suitable sound-deadening material.

Variations may be resorted to within the scope of the invention, and portions of the improvements may be used without others.

Having thus described my invention, I claim:

1. A sound-deadening casing for a typewriting machine having a carriage, said casing comprising a body-part having lateral overhangs to accommodate the travel of the carriage, and a cover extending from end to end of said overhangs and hinged to the body-part to swing from closed position to permit access to the work, said body-part being collapsible to permit it to be swung about the hinge into the cover when the casing is not in use.

2. A sound-deadening casing for a typewriting machine having a carriage, said casing comprising a body-part having lateral overhangs to accommodate the travel of the carriage, and a cover extending from end to end of said overhangs and hinged to the body-part to swing from closed position to permit access to the work, said body-part comprising foldable sections to permit it to be collapsed and swung about the hinge into the cover when the casing is not in use.

3. A sound-deadening casing for a typewriting machine having a carriage, said casing comprising a body part having lateral overhangs to accommodate the travel of the carriage, a cover hinged to said body part to swing upwardly to permit access to the work, said body part, when in operative condition, having a front opening to permit the machine to be received therethrough into the casing, and a removable front plate for closing said opening above the keyboard, and comprising foldable sections permitting the body part, when empty and with the front plate removed, to be collapsed and swung about the hinge into said cover.

4. A sound-deadening casing for a typewriting machine having a carriage, said casing comprising a body part having lateral overhangs to accommodate the travel of the carriage, and a cover hinged to said body part to swing upwardly to permit access to the work, said body part comprising a rear member receivable into said cover and side members hinged to said rear member to be swung into the latter when the machine has been removed, said rear member, with the side members therein, being swingable into said cover about the hinge connecting the body part to the cover.

5. A collapsible sound-deadening casing for a typewriting machine, said casing comprising a body part having an upright portion to receive the frame of the machine and overhanging lateral extensions to accommodate the travel of the carriage, and a cover hinged on said body part to permit access to the work and of sufficient length to cover said extensions, said body part comprising a rear member and L-shaped side members having vertical walls and horizontal floors

for said extensions of the casing, said vertical walls of the side members being hinged at their rear edges to said rear member to be swung inwardly against the latter when the machine has been removed, and to be 70 swung with the rear member about the cover hinge into said cover.

6. A collapsible sound-deadening casing for a typewriting machine having a carriage, said casing comprising a body part 75 having lateral overhangs to accommodate the travel of the carriage, and a cover hinged at the back to said body part to give access to the work, said body part comprising a rear member, side members pivotally 80 mounted on said rear member to be swung thereagainst and swung therewith into the cover, and means to limit the outward movement of each of said side members, said side members, when in their limiting positions, 85 being spaced apart at their forward edges to provide a front opening through which the machine may be inserted into the casing and through which the keyboard projects, a removable front plate to be placed 90 on said side members, after the machine is inserted, to close the opening above the keyboard, and means for detachably securing said front plate on said side members.

7. A collapsible sound-deadening casing 95 for a typewriting machine, said casing comprising a body part having an upright portion to receive the frame of the machine and overhanging lateral extensions to accommodate the travel of the carriage, and a cover hinged on said body part to permit access to the work and of sufficient length to cover said extensions, said body part comprising L-shaped side members having vertical walls and horizontal floors for said 100 extensions of the casing, and a rear member having at each end a work-sheet-receiving pocket having a front wall to which the rear edge of the adjacent side member is hinged to permit the latter to be swung to 105 bring the horizontal floor thereof against the front wall of the pocket, or to be swung inwardly to permit it to be swung with the rear member into the cover.

8. A collapsible sound-deadening casing 115 for a typewriting machine having a carriage, said casing comprising a body part having lateral overhangs to accommodate the travel of the carriage, and a cover hinged to said body part to be lifted to give access 120 to the work, said body part comprising a rear member and side members pivotally mounted on said rear member to be swung inwardly to permit the side members to be inserted in said cover by effecting a relative movement of the body part and cover about the hinge, said cover being hinged to said body part by means of co-operating knuckles on the rear member and on the cover, 125 and a pivot-rod passing through said knuck- 130

les, the mounting of said side members on said rear member comprising inwardly-extending co-operating knuckles on said rear and side members, and a pivot-rod passing 6 through said last-named knuckles.

9. A sound-deadening casing for a typewriting machine, said casing comprising a body part and a cover permitting access to the work, said body part comprising a rear 10 member to which the cover is hinged, said rear member having at its ends work-sheet-receiving pockets formed by walls extending forwardly from the edges of said member, and so spaced as to permit passage 15 thereof between the side walls of the cover, and front walls extending inwardly from the forward edges of the forwardly-extending walls, and side members having upright walls adjacent the sides of the 20 chine and horizontal floor-portions to support the cover and co-operate therewith to form lateral extensions of the casing to accommodate the travel of the carriage, the upright walls of said side members being 25 hinged at their rear edges to the rear member at the inner edges of said inwardly-extending walls to permit the side members to be positioned with the floor-portions thereof in engagement with the inwardly-extending walls of said pockets, or to be 30 swung inwardly to permit them to be swung into the cover.

10. A sound-deadening casing for a typewriting machine having a carriage, said casing 35 comprising a body part having overhangs to accommodate the travel of the carriage, a cover to give access to the work, said body part being collapsible, a hinge between said body part and cover permitting 40 the cover to be swung upwardly to permit access to the work and permitting the body part, when separated from the machine and collapsed, to swing upwardly into said cover, said body part comprising a rear member 45 by which the body part is hinged to the cover, and side members pivotally mounted on said rear member to swing from their normal positions laterally and inwardly toward said rear member to permit the rear 50 member to be swung about the hinge to carry said side members into the cover, and automatic devices for locking the side members in outward, effective position.

11. A sound-deadening casing for a typewriting machine, said casing comprising a body part and a cover part, said body part being collapsible, a hinged connection between said body part and cover part permitting the body part, when collapsed, to swing 60 upwardly into said cover part, said body part comprising a rear member by which the body part is hinged to the cover part, and side members pivotally mounted on said rear member and swingable laterally and inwardly against said rear member to in-

effective position to permit the body part to be swung into the cover part, and means carried by said side members and engaging said rear member for locking the side members in outward, effective position, said 70 means comprising a spring-catch on each of said side members, and projections on said rear member engageable by said spring-catches.

12. A sound-deadening casing for a typewriting machine, said casing comprising a body part and a cover part, said body part being collapsible, a hinged connection between said body part and cover part permitting the body part, when collapsed, to swing upwardly into said cover part, said body part comprising a rear member by which the body part is hinged to the cover part, and side members pivotally mounted on said rear member and swingable laterally and inwardly against said rear member to ineffective position to permit the body part to be swung into the cover part, and means carried by said side members and engaging said rear member for locking the side members in 90 outward, effective position, said means comprising a spring-catch on each of said side members, and projections on said rear member engageable by said spring-catches, each of said catches having a cam-surface contacting with the respective projection for holding the catch out of engagement with the projection until the side member reaches its effective, outward position, each of said catches having a finger-piece for disengaging it from the respective projection to permit the side member to be swung to ineffective position.

13. A collapsible sound-deadening casing for a typewriting machine, said casing comprising a body part and a cover part hingedly connected to said body part, said body part comprising a rear member and side members pivotally mounted on said rear member, said side members being spaced apart to provide a front opening through which the machine may be inserted in the casing, and a removable front plate mounted on said side members to close the front opening after the machine is inserted, said body part being connected to said cover part by means comprising cooperating knuckles on the rear member and on the cover part, and a pivot-rod passing through 105 said knuckles, the mounting of said side members on said rear member comprising co-operating knuckles on said rear member and on the rear edges of said side members, and a pivot-rod passing through said last-named 110 knuckles, the mounting of said front plate on said side members comprising co-operating knuckles on said front plate adjacent each side member and on the front edges of said side members, and a bolt passing 115 through said last-named knuckles.

14. A sound-deadening casing for a typewriting machine, said casing comprising a body part and a cover having side walls, said body part being collapsible and comprising a rear member hinged to the cover to permit access to the machine when in the casing and to permit the body part, when removed from the machine and collapsed, to be swung into the cover, said rear member having forwardly-extending side walls spaced to permit the passage thereof between the side walls of said cover, and side members pivoted on said rear member at the forward edges of said side walls to be swung inwardly and rearwardly against said rear member to permit the body part to be swung into the cover.

15. A sound-deadening casing for a typewriting machine, said casing comprising a body part and a cover part, said body part being collapsible, and a hinged connection between said body part and cover part permitting the body part, when collapsed, to swing upwardly into said cover part, said body part comprising a rear member by which the body part is hinged to the cover part, and side members pivotally mounted on said rear member and swingable laterally and inwardly against said rear member to ineffective position to permit the body part to be swung into the cover part, said cover part having side walls, said side members having ledges extending outwardly to support said side walls, said rear member having side pieces which fit within the side walls of the cover part when the rear member is swung upwardly, said outwardly-extending ledges being moved out of the planes of said side walls when the side members are swung against the rear member before the latter is swung upwardly.

16. A collapsible sound-deadening casing for a typewriting machine, said casing comprising a body part having an upright portion to receive the frame of the machine and overhanging lateral extensions to accommodate the travel of the carriage, and a cover hinged on said body-part to permit access to the work and of sufficient length to cover said extensions, said body part com-

prising a rear member, L-shaped side members having vertical walls and horizontal floors for said extensions of the casing, said vertical walls of the side members being hinged at their rear edges to said rear member to be swung inwardly against the latter when the machine has been removed, and to be swung with the rear member about the cover hinge into said cover, and a front member to connect said side members above the keyboard, said front member being short enough to permit it to be inserted between the sides of the cover.

17. A collapsible sound-deadening casing for a typewriting machine, said casing comprising a body part having lateral extensions to accommodate the travel of the carriage and a cover hinged to said body part and having at its front a window through which the work in the machine may be viewed, said body part comprising a rear member, side members hinged on said rear member, said side members, when in their normal positions, being spaced apart at their forward ends to provide a front opening through which the machine may be inserted in the casing, and a front plate to close the front opening over the keyboard after the machine is inserted.

18. A sound-deadening casing for a typewriting machine having a carriage, comprising a body-part having an upright portion to receive the frame of the machine and lateral overhangs to accomodate the travel of the carriage, and a cover, to permit access to the work, of sufficient length to cover said overhangs, said body-part comprising L-shaped side members having vertical walls and horizontal floors for said overhangs, and a rear member having at each end a worksheet-receiving pocket having a front wall to be engaged at its inner and upper edges, respectively, by the rear edges of the vertical and horizontal parts of said L-shaped members.

JOHN WALDHEIM.
